UNITED STATES PATENT OFFICE

156,333

HYDRAULIC PRESS

Charles K. Goldberg, Chicago, Ill.

Application August 1, 1947, Serial No. 140,670

Term of patent 14 years

(Cl. D63—1)

To all whom it may concern:

Be it known that I, Charles K. Goldberg, a citizen of the United States, residing at Chicago, Illinois, have invented a new, original, and ornamental Design for a Hydraulic Press, of which the following is a specification, reference being had to the accompanying drawings, forming a part thereof, wherein:

Figure 1 is a front perspective view of a hydraulic press, showing my new design;

Figure 2 is a rear perspective view taken from the same side of the press; and

Figure 3 is a rear perspective view taken from the opposite side of the press.

I claim:

The ornamental design for a hydraulic press, substantially as shown.

CHARLES K. GOLDBERG.
